United States Patent Office

Des. 209,780
Patented Jan. 2, 1968

209,780

PAIR OF SUNGLASSES

Anthony Shindler, Brookline, Mass., assignor, by mesne assignments, to Warner-Lambert Pharmaceutical Company, Morris Plains, N.J., a corporation of Delaware

Filed Nov. 17, 1966, Ser. No. 4,719

Term of patent 7 years

(Cl. D57—1)

Fig. 1

Fig. 2

Fig. 3

Fig. 4

Fig. 5

FIG. 1 is a perspective view of a pair of sunglasses showing my new design;

FIG. 2 is a front elevational view thereof;

FIG. 3 is a perspective view of the right side of the sunglasses shown in FIGS. 1 and 2, the side not shown being substantially of the same appearance as the side shown;

FIG. 4 is a top plan view of said sunglasses; and

FIG. 5 is a rear elevational view thereof with the temples being omitted for convenience of illustration.

The dominant features of my design reside in the portions shown in full lines.

I claim:

The ornamental design for a pair of sunglasses, substantially as shown and described.

UNITED STATES PATENT OFFICE
CERTIFICATE OF CORRECTION

Design No. 209,780

January 2, 1968

Anthony Shindler

It is hereby certified that error appears in the above numbered patent requiring correction and that the said Letters Patent should read as corrected below.

In the grant, lines 2 to 4, for "assignor, by mesne assignments, to Warner-Lambert Pharmaceutical Company, of Morris Plains, New Jersey, a corporation of Delaware," read -- assignor, by mesne assignments, to American Optical Company, of Southbridge, Massachusetts, a corporation of Delaware, --; line 14, for "Warner-Lambert Pharmaceutical Company, its successors" read -- American Optical Company, its successors --; in the heading to the drawings and printed specification, lines 3 to 5, for "assignor, by mesne assignments, to Warner-Lambert Pharmaceutical Company, Morris Plains, N. J., a corporation of Delaware" read -- assignor, by mesne assignments, to American Optical Company, Southbridge, Mass., a corporation of Delaware --.

Signed and sealed this 15th day of April 1969.
